No. 873,290.

PATENTED DEC. 10, 1907.

H. L. BEACH.
ELECTRIC APPARATUS.
APPLICATION FILED MAR. 3, 1906.

UNITED STATES PATENT OFFICE.

HOWARD L. BEACH, OF WILKINSBURG, PENNSYLVANIA, ASSIGNOR TO WESTINGHOUSE ELECTRIC & MANUFACTURING COMPANY, A CORPORATION OF PENNSYLVANIA.

ELECTRIC APPARATUS.

No. 873,290.

Specification of Letters Patent.

Patented Dec. 10, 1907.

Application filed March 3, 1906. Serial No. 304,095.

To all whom it may concern:

Be it known that I, HOWARD L. BEACH, a citizen of the United States, and a resident of Wilkinsburg, in the county of Allegheny and 5 State of Pennsylvania, have invented a new and useful Improvement in Electric Apparatus, of which the following is a specification.

My invention relates to electric apparatus 10 and has special reference to electrically-operated means for producing a step-by-step movement of a device.

One object of my invention is to provide a device of the class above indicated, that shall 15 be simple and durable in construction, that shall automatically and successively complete a series of circuit connections and that shall be dependent upon the opening and closing of a single circuit.

20 A further object of my invention is to provide means for automatically returning the aforesaid device to its initial position upon the interruption of a predetermined circuit.

In the operation of variable speed motors, 25 such as are employed for electric railway vehicle service, it has been found desirable and economical to employ a system of automatic acceleration which has usually comprised a plurality of switches so interlocked as to 30 confine their operation to a predetermined sequence. With such an arrangement, it is advisable to use a device for preventing the closure of each accelerating switch until the current flowing in the motor circuit falls 35 below a predetermined value, in order that the motors may not be injured by increasing the applied voltage too rapidly. When such systems are applied to electric locomotives which are utilized for propelling or 40 hauling trains of different lengths and weights it is of special advantage to provide means for adjusting the predetermined current value at which the limiting device will operate in order that the time consumed in 45 the acceleration may be kept substantially constant for all loads. A device for accomplishing this purpose may comprise a plurality of switches having dissimilar actuating coils, all of which are connected in series 50 relation with the motor circuit. In order that means of this character may be under the control of the attendant, it is necessary to provide a selective device whereby the limit switch which is adapted to the service

conditions imposed upon the vehicle, may be 55 actively connected in the control circuits.

According to my present invention, I provide a device comprising two electro-magnets, one of which, when deenergized, automatically returns the device from any of the 60 operating positions which it is adapted to occupy, to its initial position, and the other of which, when successively energized and deenergized, moves the device through its several operating positions. The supply of 65 energy to the first electro-magnet may advantageously be dependent upon the position occupied by a master controller and that to the other may preferably be dependent upon a push button switch or similar device which normally interrupts the circuit. Although the apparatus of my invention is 70 specially adapted for use with the adjustable limiting device hereinbefore described, its use is not restricted thereto, and although the 75 step-by-step movement is utilized for moving the contact member successively into engagement with a series of stationary contact fingers for effecting desirable circuit connections, I desire that my invention 80 shall be construed to cover the application of such a motion for any other purpose to which it is adapted.

My invention is illustrated in the accompanying drawings in which 85

Figure 1 is a sectional elevation of a device constructed in accordance therewith. Fig. 2 is a plan view of a portion of the device illustrated in Fig. 1 and Fig. 3 is a diagrammatic view of a system embodying an application of my invention to an adjustable 90 limiting device.

Referring particularly to Figs. 1 and 2, the device illustrated therein comprises electro-magnets 1 and 2 having movable core members 3 and 4, a ratchet member 5, a movable contact member 6 and engaging fingers 7, 8, 9 and 10. The ratchet member 5 and the contact member 6 are attached to opposite extremities of a connecting rod 11 which extends through a hole in the movable core member 4 of electro-magnet 2, in which it is free to operate. The ratchet member 5 may be engaged by a pair of pawls 12 which are pivotally connected to the movable core 95 member 3 of the electro-magnet 1 and by a pair of stationary pawls 13. The motion of the movable core member 3 is limited on one 100

105

90

100

105

side by a stationary core member 14 and on the other side by a collar or cap 15 which is attached adjustably to the cover plate 16 of the electro-magnet. When the electro-magnet 1 is deenergized the core member 3 is held in engagement with the cap 15 by the action of a spring 17 which is compressed when the coil is energized. A spring 18 is interposed between a shoulder 19 on the rod 11 and the movable core member 4 of the electro-magnet 2 in order to force the rod 11 and the said core member in opposite directions and normally hold the latter against a cap or collar 21, which corresponds to the cap or collar 15 of the electro-magnet 1. The outer end of the movable core member 4 is beveled and when the electro-magnet 2 is deenergized it is adapted to move the pawls 12 and 13 out of engagement with the ratchet member 5, against the action of springs 22 and 23, by reason of the pressure of the spring 18. The ratchet member 5 is provided with notches 24, 25, 26 and 27 and the arrangement of the parts is such that when current is supplied to electro-magnet 2, and electro-magnet 1 is deenergized, both pairs of pawls 12 and 13 engage the notch 24 and the contact finger 7 engages the movable contact member 6. If the electro-magnet 1 is then energized, the core member 3 is moved into engagement with the stationary core member 14, against the action of the spring 17, and the ratchet member 5, the connecting rod 11 and the movable contact member 6 are moved by the pawls 12 until the stationary pawls 13 engage the notch 25. If the supply circuit of the electro-magnet 1 is again interrupted, the spring 17 changes the position of the core member 3 and moves the pawls 12 into engagement with the notch 25. In a similar manner, by continuing to intermittently energize the electro-magnet 1, the stationary pawls 13 successively engage the notches 26 and 27 and the movable contact member 6 is moved successively into engagement with contact fingers 9 and 10. If the electro-magnet 2 is deenergized at any stage of the operation, the ratchet member 5 is immediately released from the pawls 12 and 13, by the movable core member 4, and the contact member 6 is returned to its initial position by the action of the spring 18.

The application of the device, in a system to which it is adapted, is illustrated in Fig. 3 to which reference may now be had. The system here illustrated comprises an electric motor 28, resistance sections 29 and 29^a which may be connected in series circuit relation therewith, switches 30, 31 and 31^a which determine the circuit connections therefor, a limiting device 32 and a master switch 33 which is adapted to occupy either of positions *x* and *y*. When the master switch occupies the position *x* the control circuits are interrupted and the switches 30

and 31 are open. When the master switch is moved to the position *y* energy is supplied from any convenient source, such as a battery 34, through contact finger 35 and contact member 36 to the contact finger 37. From the contact finger 37, energy is supplied through conductor 38 to one terminal of the winding of the electro-magnet 2, the opposite terminal of which is connected to the negative terminal of the battery 34. As soon as this winding is energized, the pawls 12 and 13 engage the notch 24 of the ratchet member 5. Current is supplied to an operating magnet winding 48^a of the switch 31^a through a conductor 39 and, as soon as the switch is closed, a circuit is completed from line conductor 57 through switch 31^a, resistance 29^a, motor 28, limit coils 61, 60, 59 and 58 and resistance section 29 to conductor 62. Current is now also supplied from contact finger 37 through conductor 39 to contact member 6, contact finger 7, limit switches 40, 41, 42 and 43, conductor 44, contact finger 45^a of the switch 31^a, contact member 46^a, contact finger 47^a, contact finger 45 of the switch 30, contact member 46 and contact finger 47, to operating magnet 48, the opposite terminal of which is connected to the negative terminal of the battery 34. Energy may be supplied to the coil 48 and the switch 30 may be closed if the limit switches 40, 41, 42 and 43 are closed. As soon as the switch 30 is closed, energy is supplied directly from the conductor 39 through contact finger 49, contact member 46 and contact finger 47 and the coil 48 so that the switch is held in this position irrespective of the subsequent action of the limit switches. Energy is now supplied through the limit switches and conductor 44 through contact finger 45 which engages contact member 50, contact finger 51, conductor 52, contact finger 53 of the switch 31, contact member 54 and contact finger 55 and the operating coil 56 of the switch 31. The opposite terminal of the coil 56 is connected directly to the negative battery terminal. The successive closing of the switches 30 and 31 short-circuits the resistance sections 29^a and 29 so that the motor is finally connected directly across the line.

The acceleration of the motor 28, as hereinbefore described, is dependent upon the closure of all of the limit switches when the contact member 6 engages the contact finger 7. If it is desirable, however, to accelerate the motor more rapidly, the electro-magnet 1 may be temporarily energized by closing the push button switch 63 in order to supply electric current to the magnet winding 125 through the conductor 38. If this magnet is energized when the pawls 12 are in engagement with the notch 24 on the ratchet member 5, the contact member 6 is moved into engagement with contact finger 8 and the

pawls 13 engage the notch 25. The pawls 12 move into engagement with the notch 25 as soon as the electro-magnet 1 is deenergized. When the contact member 6 engages contact finger 8, energy is supplied from the conductor 39 to a point intermediate the switches 40 and 41 so that the acceleration of the motor is independent of the limit switch 40. The acceleration of the 10 motor may be still further increased by again closing the switch 63 which connects conductor 39 to a point between switches 41 and 42, so that the acceleration becomes independent of the switch 41. In a similar 15 manner, the acceleration of the motor may be made independent of the switch 42 since the convolutions included in the windings 58, 59, 60 and 61 are so determined as to open the switches 40, 41, 42 and 43 at materially increased current values flowing in the 20 motor circuit.

The details of construction may, of course, be varied within considerable limits without departing from my invention.

25 I claim as my invention:

1. The combination with a movable contact member having a ratchet device, and actuating and holding pawls to engage said device, of a spring and an electro-magnet 30 acting alternatively and oppositely upon the actuating pawls, means for holding the pawls out of engagement with the ratchet device, and a spring and an electro-magnet acting alternately and oppositely upon said means.
- 35 2. The combination with a movable contact member having a ratchet device and stationary contact fingers, of actuating and holding pawls, an electro-magnet for moving the actuating pawls forwardly and a spring 40 for moving them rearwardly to effect a step-by-step movement of the contact member to engage said fingers successively; and a spring-actuated means for releasing the ratchet device from the pawls.
- 45 3. The combination with a movable contact member having a ratchet device and stationary contact fingers, of electro-magnetically-actuated pawls for automatically moving said member into engagement with said 50 fingers successively; and springs for moving said pawls rearwardly and for moving them out of engagement with the ratchet device.
- 55 4. The combination with a longitudinally movable contact member, stationary contact terminals and a ratchet member attached to the movable member, of pawls for 60 engaging the ratchet member, an electro-magnet and a spring acting in opposition upon said pawls to move the contact member step-by-step into engagement with the stationary 65 fingers successively, means for holding said member in each position to which it is moved, and means for releasing the ratchet member

from the pawls when the interruption of the circuit is desired. 65

5. The combination with a longitudinally movable contact member, stationary contact terminals and a ratchet member attached to the movable member, of electro-magnetically-actuated means for engaging 70 the ratchet member to move the contact member step-by-step into engagement with the stationary terminals successively, and means for holding the movable member in each position to which it is moved. 75

6. The combination with a longitudinally movable contact member, stationary contact terminals, and a ratchet member attached to the movable member, of means for engaging the ratchet member to move the 80 contact member step-by-step into engagement with the stationary terminals successively, means for holding the movable member in each position to which it is moved, means for releasing said member and means 85 for returning it to its initial position.

7. The combination with a longitudinally movable contact member, stationary contact terminals, a ratchet member attached to the movable member, and a pair of pawls 90 adapted to engage said ratchet member to hold the movable member in a predetermined position, of electro-magnetically-actuated means for engaging the ratchet member to move the contact member into engagement with the said terminals successively. 95

8. The combination with a longitudinally movable contact member, stationary contact terminals, a ratchet member attached to the movable member, and a pair of pawls 100 adapted to engage said ratchet member to hold the movable member in a predetermined position, of a pair of electro-magnetically-actuated pawls to engage said ratchet member and move the contact member step- 105 by-step into engagement with the said terminals successively.

9. The combination with a longitudinally movable contact member, stationary contact terminals, a ratchet member attached 110 to the movable member, a pair of pawls adapted to engage said ratchet member and to hold the movable member in a predetermined position, of means for engaging said ratchet member to move said contact member step-by-step into engagement with the 115 said terminals successively, and means for releasing and returning the movable member to its initial position.

10. The combination with a longitudinally 120 movable rod, a ratchet member and a contact member attached thereto, stationary contact fingers to engage said contact member, a pair of stationary pawls which may be held in engagement with said ratchet member, an electro-magnet, a pair of pawls at 125

- tached to the movable core of said electro-magnet, means for releasing both pairs of pawls, and an actuating spring therefor that serves to return the contact member to its initial position.
11. The combination with a longitudinally movable rod, a ratchet member and a contact member attached thereto, stationary contact fingers to engage said contact member, a pair of stationary holding pawls to engage said ratchet member, an electro-magnet, a pair of engaging pawls attached to the movable core of said electro-magnet, means for releasing both pairs of pawls, an actuating spring therefor that serves to return the contact member to its initial position, and an electro-magnet that acts in opposition to said spring.
12. The combination with an operating rod, a contact member attached thereto and insulated therefrom, stationary engaging contact fingers, a series of notches at the opposite extremity of the rod, stationary pawls adapted to engage said notches and confine the motion of said rod to one direction, of an electro-magnet, a movable core member therefor, and pawls attached thereto and adapted to engage the notches on the rod.
13. The combination with an operating rod, a contact member attached thereto and insulated therefrom, stationary engaging contact fingers therefor, a series of notches at the opposite extremity of the rod, stationary pawls adapted to engage said notches and confine the motion of said rod to one direction, of an electro-magnet, a movable core member therefor, pawls attached thereto and adapted to engage the notches on the rod and means for bringing the contact member into successive engagement with said stationary contact fingers.
14. The combination with an operating rod, a contact member attached thereto and insulated therefrom, stationary engaging contact fingers therefor, a series of notches at the opposite extremity of the rod, stationary pawls adapted to engage said notches and confine the motion of said rod to one direction, of an electro-magnet, a movable core member therefor, pawls attached thereto and adapted to engage the notches on the rod and means for bringing the contact member into successive engagement with said stationary contact fingers as said electro-magnet is intermittently energized.
15. The combination with an operating rod, a contact member attached thereto and insulated therefrom, stationary engaging contact terminals therefor, a series of notches at the opposite extremity of the rod, stationary pawls adapted to engage said notches and confine the motion of said rod to one direction, of an electro-magnet, a movable core member therefor, pawls attached thereto and adapted to engage the notches on the rod and
- means for bringing the contact member into successive engagement with said stationary contact terminals as said electro-magnet is intermittently energized, and means for releasing the pawls from the notches and returning the rod to its initial position.
16. The combination with an operating rod, a contact member attached thereto and insulated therefrom, stationary engaging contact fingers, notches on one end of the rod, engaging pawls operated by an electro-magnet to move the contact member into successive engagement with the stationary fingers, stationary pawls adapted to retain the movable contact member in position as it is advanced through successive steps.
17. The combination with an operating rod, a contact member attached thereto and insulated therefrom, stationary engaging contact terminals, notches on one end of the rod, engaging pawls operated by an electro-magnet to move the contact member into successive engagement with the stationary terminals, stationary pawls adapted to retain the movable contact member in position as it is advanced through successive steps and means for releasing the stationary and the movable pawls from engagement with said notches, said means being operative when a second electro-magnet is deenergized.
18. In a system of electric motor control, the combination with switches adapted to close in a predetermined sequence, of limit switches adapted to operate at different values of electric current and to retard the closure of said switches, and selective means for determining which of said limit switches shall be included in the circuit, said means comprising a movable contact member, stationary contact fingers and electro-magnetic means for moving said member into successive engagement with said fingers.
19. In a system of electric motor control, the combination with switches adapted to close in a predetermined sequence, of limit switches adapted to operate at different values of electric current and to retard the closure of said switches, and selective means for determining which of said limit switches shall be included in the circuit, said means comprising a movable contact member, stationary contact terminals and electro-magnetic means for moving said member into successive engagement with said terminals by temporarily and intermittently closing a single electric circuit.
20. In a control system for electric motors, the combination with switches provided with auxiliary interlocking contact members to determine the relative position and the sequence of operation of the switches and a plurality of dissimilar magnet windings connected in series relation with the motor circuit and adapted to open the auxiliary supply circuits when predetermined values traverse the

motor circuits, and selective means for determining which of said limit switches shall be included in the circuit, said means comprising a movable contact member, stationary 5 contact fingers and electro-magnetic means for moving said member into successive engagement with said fingers.

21. In a control system for electric motors, the combination with switches provided with 10 auxiliary interlocking contact members which determine the relative position and the sequence of operation of the switches and a plurality of dissimilar magnet windings connected in series relation with the motor circuit and adapted to open the auxiliary supply circuits when predetermined values traverse the motor circuits, and selective means for determining which of said limit switches shall be included in the circuit, said means 20 comprising a movable contact member, stationary contact terminals and electro-magnetic means for moving said member into successive engagement with said terminals by temporarily and intermittently closing a 25 single electric circuit.

22. In a control system, the combination with electric motors, resistance in circuit therewith and switches adapted to effect suitable circuit connections and to gradually 30 short-circuit the resistance by the closure of said switches in a predetermined sequence, and a limiting device which automatically in-

terrupts the interconnecting control circuits so that the normal sequential operation is delayed, of controlling and adjusting means for 35 said limiting device comprising a movable contact member, stationary contact terminals, and electro-magnetic means for moving said member into successive engagement with said terminals. 40

23. In a control system, the combination with electric motors, resistance in circuit therewith and switches adapted to effect suitable circuit connections and to gradually short-circuit the resistance by the closure of 45 said switches in a predetermined sequence and a limiting device which automatically interrupts the interconnecting control circuits so that the normal sequential operation is delayed, of controlling and adjusting means for 50 said limiting device, comprising a movable contact member, stationary contact terminals, and electro-magnetic means for moving said member into successive engagement with said terminals temporarily and intermittently closing a single electric circuit. 55

In testimony whereof, I have hereunto subscribed my name this 28th day of February 1906.
